UNITED STATES PATENT OFFICE

HERMAN A. FEIGELMAN, OF PATERSON, NEW JERSEY

GARMENT HANGER

Application filed December 19, 1928. Serial No. 327,075.

The object of this invention is to provide a garment hanger which may be cheaply made and yet will be strong, light, durable and capable of being packed with other articles, as with clothing in a trunk, without occupying appreciable space. While the hanger may be made of other sheet material, it is so constructed as to have ample strength, at least for the support of certain lighter garments, when made of cardboard.

In the drawings,

Fig. 1 is a plan of the blank from which the device is formed;

Figs. 2 and 3 show the device in section in substantially a vertical central plane in two stages of its development from the blank;

Fig. 4 is a front elevation of the completed device;

Figs. 5 and 6 are sectional views on line 5—5 and 6—6, respectively, Fig. 4;

Figs. 7 and 8 are a plan of the blank and a front elevation of the finished device, showing a slight modification;

Figs. 9, 10 and 11 are, respectively, a plan of the blank, a front elevation and a section on line 11, Fig. 9, showing another modification; and

Figs. 12 and 13 show a modification, Fig. 12 being an elevation and Fig. 13 a section on line 13—13, Fig. 12.

A blank of flexible but stiff sheet material, as cardboard, is formed with an elongated body portion 1 having a pair of opposite tongues 2^a, 2^b, which may be either shaped as hooks, Figs. 1 to 8, or as loops or eyes, Figs. 9 to 11, since they are to afford in the completed article the suspending means thereof. Said body portion is to be folded on the longitudinal line, as 3, to form the hanger bar or body part *a* (Fig. 4) of the device, and coinciding with said line is a slot 4; in one (1^b) of the plies or leaves 1^a, 1^b, resulting from such folding a longitudinal slit may be formed to afford another slot 5.

To form the device in the example shown the body portion 1 is folded on line 3, producing the said plies or leaves 1^a, 1^b, and consequently the hanger bar *a*. Tongue 2^b is then bent toward leaf 1^a and so as to extend between the plies or leaves and through slot 4 (Fig.

2), a fold being preferably formed at 6^b at the base of the tongue 2^b. Tongue 2^a is next bent toward the leaf 1^b but so as to extend around said bend 6^b and outwardly of leaf 1^b and also through first slot 5 and then through slot 4 (Fig. 3), a fold being preferably formed at 6^a at the base of such tongue 2^a (Fig. 5). When the device is formed in this particular manner it has considerable stability and strength, the different parts being firmly secured in their final arrangement and the device being two-ply throughout excepting the zone where the tongues cross the leaves 1^a, 1^b, where it has desirable extra (four-ply) thickness.

At a distance from the outer longitudinal margin of each leaf or ply equal to the transverse dimension of the latter each tongue has shoulders 7 which in the completed hanger bear within and against the fold at line 3 (Fig. 4). If it is desired to bevel or slope the upper corners of the hanger bar of the hanger this may be done by folding downward and between the plies on lines inclined downwardly toward the terminals of the hanger bar portions of said plies, as by slitting the material of the hanger bar at 8 on lines coincident with line 3 and folding the material inwardly and downwardly on the converging lines 9. In the case of certain women's garments having shoulder straps, the latter may be accommodated in notches 10 formed in the hanger bar.

In Figs. 9 to 11 a hanger is shown for supporting men's suits, including trousers. In this case the hanger bar has spaced depending slings or loops, and a bar is carried by these slings and is adapted to support the trousers. In the particular construction shown the plies or leaves 1^a, 1^b have at their ends extensions 11 of which one at each end of either ply is opposed by an extension at the corresponding end of the other leaf. Both such extensions are folded on lines 12 extending parallel with line 3 toward each other, one folded extension embracing the other, and one has a lateral tab or hook 13 which may be folded back on lines 14 and engaged and locked in a slit 15 in such extension. Thus is formed a loop or sling closed

at the outer side but open at the inner side and such two slings are adapted to receive the ends of a bar 16 for supporting the trousers.

- 5 In Figs. 12 and 13 a suitably-formed blank is folded on line 17, the same having a tongue or tongues 18 which project in transverse relation to said line and are opposite each other; the blank also has on one ply each 10 side of one tongue tabs 19 which after folding the blank to form the two plies are bent over the edge of the other ply and entered into slits 20 in the latter, thus locking the two plies together.
- 15 In the broadest aspect of my invention the garment hanger consists of a blank of flexible stiff sheet material having a tongue projection to form a suspender (for instance 2^b in Fig. 1 or either tongue in Fig. 13) extending 20 from one edge of the blank and said blank being folded on a line transverse of the direction in which the tongue projection extends and thus forming a two-ply hanger bar, and having means (for instance, tongue 25 2^a in Fig. 1 engaged in slit 5 or the tabs 19 in Fig. 13 entered into slits 20) to lock the two plies together.

Having thus fully described my invention, what I claim is:

- 30 1. A garment hanger consisting of a blank of flexible stiff sheet material folded to form an elongated two-ply hanger bar and having a tongue extending from one ply of the hanger bar transversely of the line of fold 35 and said tongue rebent and protruding through the part of said material forming the hanger bar and forming the suspender of the hanger.
2. A garment hanger consisting of a blank 40 of flexible stiff sheet material folded to form an elongated two-ply hanger bar and having a tongue extending from one ply of the hanger bar transversely of the line of fold and said tongue rebent and protruding 45 through the part of said material forming the hanger bar in substantial coincidence with the line of the fold and forming the suspender of the hanger.

3. A garment hanger consisting of a blank 50 of flexible stiff sheet material folded to form an elongated two-ply hanger bar and having tongues extending from the respective plies oppositely to each other and said tongues rebent and their rebent portions protruding 55 through the part of said material forming the hanger bar and thereby forming suspending means for the hanger.

4. A garment hanger consisting of a blank 60 of flexible stiff sheet material folded to form an elongated two-ply hanger bar and having an aperture in its hanger-bar-forming portion and also having tongues extending from the respective plies and said tongues rebent and their rebent portions both protruding 65 through said aperture and from said portion

and thereby forming suspending means for the hanger.

5. A garment hanger consisting of a blank of flexible stiff sheet material folded to form an elongated two-ply hanger bar and having 70 tongues extending from the respective plies oppositely to each other and said tongues rebent toward each other and their rebent portions protruding through the part of said material forming the hanger bar and thereby forming suspending means for the hanger. 75

6. A garment hanger consisting of a blank of flexible stiff sheet material folded to form an elongated two-ply hanger bar and having 80 separate apertures in its hanger-bar-forming portion and also having tongues extending from the respective plies and said tongues rebent and their rebent portions protruding through the respective apertures and from said portion and thereby forming suspending 85 means for the hanger.

7. A garment hanger consisting of a blank of flexible stiff sheet material folded to form an elongated two-ply hanger bar and having 90 two apertures, one substantially coincident with the line of fold and one in one ply, said blank also having tongues extending from the respective plies and rebent toward each other, the tongue which extends from the ply having the latter aperture being arranged to protrude through the first aperture and the other tongue being arranged to extend outwardly of such ply and then to protrude first through the second and then through the first aperture and said 95 tongues thus forming suspending means for the hanger. 100

8. A garment hanger including a two-ply hanger bar formed by folding a blank of flexible stiff sheet material and having means to suspend the hanger bar with the fold upward, portions of the plies at both ends of the hanger bar being folded downward and between the plies on lines inclined downwardly toward the terminals of the hanger 105 bar, thus forming upper slopes on said ends. 110

9. A garment hanger including a two-ply hanger bar formed by folding a blank of flexible stiff sheet material and having means to suspend the hanger bar with the fold upward, said hanger bar having spaced depending slings, and a bar carried by said slings. 115

10. A garment hanger including a two-ply hanger bar formed by folding a blank of flexible stiff sheet material and having means to suspend the hanger bar with the fold upward, the blank having at the ends of the hanger bar spaced downward loop extensions, and a bar received in and carried by 120 said loop extensions. 125

11. A garment hanger consisting of a blank of flexible stiff sheet material having a tongue projection to form a suspender extending from an edge of the blank and said 130

blank being folded on a line transverse of the direction in which the tongue projection extends and thus forming a two-ply hanger bar and having means to lock the two plies of the
5 hanger bar together.

In testimony whereof I affix my signature.

HERMAN A. FEIGELMAN.
